[57] CLAIM

I claim the ornamental design for a physical therapy board,
as shown.

DESCRIPTION

FIG. 1 is a front perspective view of a physical therapy board,
showing my new design;

FIG. 2 is a top view thereof.

FIG. 3 is a front elevational view thereof.

FIG. 4 is a rear elevational view thereof.

FIG. 5 is a left side elevational view thereof.

FIG. 6 is a right side elevational view thereof; and,

FIG. 7 is a front perspective view of second embodiment of
the physical therapy board, showing my new design.
